(57) **CLAIM**

The ornamental design for a container for dispensing bagged liquids, as shown and described.

DESCRIPTION

FIG. 1 is a front, left perspective view of a container for dispensing bagged liquids showing my new design; FIG. 2 is a front elevation view of the container for dispensing bagged liquids thereof; FIG. 3 is a rear elevation view of the container for dispensing bagged liquids thereof; FIG. 4 is a right elevation view of the container for dispensing bagged liquids thereof; FIG. 5 is a left elevation view of the container for dispensing bagged liquids thereof; FIG. 6 is a top plan view of the container for dispensing bagged liquids thereof; FIG. 7 is a bottom plan view of the container for dispensing bagged liquids thereof; and, FIG. 8 is bottom perspective view of the container for dispensing bagged liquids thereof. The dot-dash broken lines show a boundary of the claim, and form no part of the claimed design.
